UNITED STATES PATENT OFFICE.

ATWELL J. BLACKFORD, OF CLEVELAND, OHIO, ASSIGNOR TO AMERICAN STOVE COMPANY, OF ST. LOUIS, MISSOURI, A CORPORATION OF NEW JERSEY.

BLUE-FLAME OIL-STOVE.

1,074,686.

Specification of Letters Patent.

Patented Oct. 7, 1913.

Application filed November 12, 1912. Serial No. 730,985.

To all whom it may concern:

Be it known that I, ATWELL J. BLACKFORD, a citizen of the United States, residing at Cleveland, in the county of Cuyahoga and State of Ohio, have invented certain new and useful Improvements in Blue-Flame Oil-Stoves, of which the following is a specification, reference being had therein to the accompanying drawing.

10 This invention relates to improvements in blue flame oil stoves, and is an improvement on a type of burner in which there is a vapor generating flame which generates an excess of vapor that afterward has air mixed therewith in proper quantities and then passed through a blue flame burner-cap, which produces a blue-flame of large extent and maximum heating efficiency.

15 My present improvement generically considered pertains to providing a yellow initial heating flame adapted to be converted into a vapor generating blue flame, which generates an excess of vapor, the excess of vapor having air mixed with it and passed

20 through a suitable blue flame burner-cap for producing the final flame for cooking purposes.

A further object of my present invention is to provide means for drawing vapor from 30 at, or approximately at the blue flame vapor generating flame to supply vapor for the final working blue flame.

I am aware that Edward Boeckenkamp, of St. Louis, Missouri, has devised a burner 35 in which there is a blue flame initial heating and a blue flame vapor generating flame for generating excess vapor to be supplied with air and finally burned at a blue flame burner-cap, but my improvement is broadly the 40 means for providing an initial heating yellow flame adapted to be converted into a vapor generating blue flame, and to provide the excess vapor in a different manner from that in the aforesaid Boeckenkamp burner.

45 I find that the parts of the burner can be more efficiently and more quickly heated up by the yellow flame than by the initial heating blue flame, and I also find that there are certain other advantages in my improved 50 manner of obtaining the excess vapor for the final working flame.

In the accompanying drawings—Figure 1 is a perspective view of the burner involving my improvement. Fig. 2 is a sectional view of the burner, the chimney having been 55 shown in side elevation. Fig. 3 is a sectional view of the chimney and the inner tube. Fig. 4 is an enlarged inverted plan view of the slotted blue flame burner cap. Fig. 5 is a sectional view of a modification 60 in the form of a chimney. Fig. 6 is an inverted plan view of the cap or deflector for the initial heating and vapor generating burner, showing the converter and draft tube in position.

65 Referring now to the drawings, 1 is a base within which is located the wick-tube 2, containing a vertically adjustable wick 3. This wick is vertically adjustable by means of a thumb-screw 4, and any form of intervening 70 mechanism (not shown) for raising and lowering the wick. A burner-cap or deflector 5 rests upon and is adjusted up and down with the wick, this cap being movable on a rod 6 carrying a stop 7 at its upper end.

75 The cap or deflector 5 comprises a sleeve portion 8, projecting down within the wick-tube, which has a series of arms 9 projecting radially from the said flange 8 and resting on the wick 3. An annular flange 10 80 projects outward above the arms 9, and this flange is provided around its edge with the openings 11.

A perforated vertically arranged annular gallery 12 surrounds the burner-cap 5, and a 85 removable chimney 13 has its outer end fitting around and surrounding a flange 14, which flange is spaced from the gallery 12. The flange 14, chimney 13 and gallery 12 are removable together, all being supported in position by the lower end of the gallery 12, resting in an annular cup-shaped flange 15, extending out from the upper end of the wick-tube 2. As shown in Figs. 1 to 3 inclusive, the chimney 13 is tapered or contracted upwardly. Located within this chimney is a straight wall tube 16 to which is attached a rod or handle 17 passed outwardly through a bayonet joint-shaped slot 18, by means of which the tube 16 may be 100 raised and locked in this raised position, as shown in Fig. 3, and then lowered, as

shown in dotted lines Fig. 2. This tube 16 has its lower edge flanged outward and provided with perforations 19. Just above the perforations the tube is provided with several inwardly extending punched projections 20, and the tube is provided with a plurality of openings 21, located at a point about one-fourth the distance of its length from its lower end. The upper end 22 of the tube is opened into the upper end of the chimney 13 and immediately below the slotted blue flame burner-cap 23.

When the tube 16 is lowered into operative position around the cap 5, there is an annular space 24 between its lower end and the burner-cap 5 for a purpose to be presently described.

The object of having the tapered chimney and the straight wall tube 16 is to enable the tube and other parts to be more readily heated in the initial heating and to be more readily kept hot in the normal operation of the burner, and thereby more efficiently prevent any condensation of the vapor on the walls of either the chimney or the tube.

In Fig. 5 I show a modification of the chimney in providing the upper portion with a straight wall 13', and its lower end enlarged outward, as shown at 14'. In all other respects the burner is like that shown in Figs. 1, 2, 3 and 6, and the operation substantially the same.

In operation the wick is turned up carrying with it the burner-cap 5, to expose the wick. The chimney is then removed, taking with it the gallery 12, flange 14 and tube 16. The wick is then lighted, the parts placed in position with the tube 16 elevated, as shown in Fig. 3. There is then produced a yellow flame of considerable extent. This yellow flame heats the tube 16, the chimney 13, the burner-cap 23 and in general the surrounding parts of the burner. When the parts have become thoroughly heated, the tube 16 is lowered to the position shown in dotted lines, Fig. 2, which converts the yellow flame into a blue flame. This conversion of the yellow flame naturally reduces the size of the flame and at the same time this tube 50 when in this lowered position causes a decided draft right at the wick or burning point, and this draft sucks the vapor from behind the wick between the arms 9, and through the openings 11, in the flange 10, 55 and also draws some of the vapor from the flame. This draft which thus draws the vapor robs the flame, and, of course, reduces the flame so that there is a small blue flame as compared to the original yellow flame 60 and an excess amount of vapor which is drawn upward into the tube 16. This vapor has already mixed with it a considerable amount of air caused by the draft drawing the air with the vapor through the passages 65 formed by the arms 9 and openings 11 and

19, practically sufficient to cause it to burn with the blue flame at the burner-cap 23. The vapor is also drawn through the annular space 24, between the lower end of the tube 16 and the burner-cap. For the purpose of accelerating the draft through the tube and to add a little more air to the vapor, I provide a plurality of openings 21 in the tube 16, which I find materially accelerates the draft therein for drawing the vapor from the vaporizing point of the wick and flame and materially improves the final flame burning at the working burner 23 at the top of the chimney.

Having thus described my invention, what I claim and desire to secure by Letters Patent is:

1. A burner of the type described, comprising a chimney having a blue flame burner-cap at its top, an initial heating yellow flame burner within the lower end of the chimney, a movable tube within the chimney adapted to surround the burner and convert the yellow flame into a blue flame, said tube having air passages therethrough for creating a draft and mixing air with the excess vapor and drawing it through the blue-flame burner and forcing it through the aforesaid blue flame burner-cap at the top of the chimney.

2. A burner of the type disclosed having a chimney with a blue flame burner-cap at its top, an initial heating yellow flame burner within the lower end of the chimney, a vertically movable tube within the chimney and adapted to surround the yellow flame burner to convert it into a blue flame burner, said tube having openings at its lower end.

3. A burner of the type disclosed, comprising a chimney having a blue flame burner at its top, an initial heating yellow flame burner within the lower end of the chimney, a vertically movable tube within the chimney and adapted to have its lower end surround the burner to convert the yellow flame into a blue flame, said tube having air passages at its lower end and passages intermediate its ends.

4. A burner of the type disclosed, comprising a chimney having a blue flame burner-cap at its top, an initial heating yellow flame burner within the lower end of the chimney and an elongated open ended vertically movable tube within the chimney and adapted to have its lower end surround the burner to convert the yellow flame into a blue flame, said chimney creating a draft to draw the excess vapor through the tube and delivering it to the burner-cap at the upper end of the chimney.

5. A burner of the type disclosed, comprising a chimney having a blue flame burner-cap at its top, an initial heating yellow flame burner within the lower end of

the chimney, a vertically movable tube within the chimney at its lower end and adapted to surround the burner, the burner having air passages located in a vertical plane within the lower end of the tube through which air and excess vapor are drawn and conveyed to the burner-cap at the top of the chimney.

In testimony whereof I hereunto affix my signature in the presence of two witnesses.

ATWELL J. BLACKFORD.
